Design No. 150

No 150

Gale & Hayden's Spoons
Patented Sept 11th 1847

Des. 150

William Gale & Nathaniel Mayden New York
Letters Patent (Design No 150) Dated 11th Sept 1827

The schedule referred to in these Letters Patent and making part of the same.

To all whom it may concern: Be it known that we William Gale & Nathaniel Haydon of the City County & State of New York being co-partners in the Silver Smith business under the firm of Gale & Haydon and residents in said City have invented & produced a new ornamental design for embossing beautifying the handles of Spoons, Forks, Butter Knives, Fish knives, Ladles and other articles of Silver table Ware, and do declare the following is a full and exact description of the same.

Figures 1 and 2 obverse and reverse sides of a spoon handle ornamented mostly with gothic ornaments as shown by letters on each part referred to in this specification of the same, as follows, the broad part of the handle at the upper end is an arch A running up to a point at the top of the handle, the whole arch encircled with a vine or creeper B in which arch is a gothic window or opening C; below the opening is a double arch D each side resting on caps E of two perpendicular pillars F, inside of these pillars is a light edge G running up under the double arch above, and resting on caps I below with the straight pillars on each side a little above the caps I on each side are double scrolls L from which runs an inverted gothic arch M, from which arch there is a small leaf N running with the arch down on the narrow part of the handle. On each side is a groove or concave edge O finishing at the top in a plain scroll on which rests the caps I that support the straight pillars, and finishing on each side near the bowl of the spoon P in a double leaf Q. Said groove forming an edge or single thread on the main body of the handle R.

The reverse or back of the handle has precisely the same figures as the front excepting that part S running down on the back of the bowl, which is wider than the front, and finishes in an inverted arch T all of which will more fully appear by referring to the drawings accompanying this marked Wm Gale, Nathl Haydon New York Aug. 1st 1847.

Having now described the various devices and arrangements of the same for the purpose of ornamenting the handles of

Dec. 150

Spoons, Forks, Butter Knives, Fish Knives, Ladles and other articles of Table Silver ware, we will proceed to state what we claim and what we wish to secure by Letters Patent.

First the particular device as shown in the drawings and explained above for ornamenting the obverse and reverse sides of Spoons Forks &c.

Second the combination of the form of the handle with the ornaments and the particular arrangements of the devices.
